UNITED STATES PATENT OFFICE.

WALTER S. ADAMS, OF PHILADELPHIA, PENNSYLVANIA, ASSIGNOR TO
JOHN A. BRILL, OF PHILADELPHIA, PENNSYLVANIA.

MAXIMUM-TRACTION TRUCK.

SPECIFICATION forming part of Letters Patent No. 761,347, dated May 31, 1904.

Application filed September 16, 1903. Serial No. 173,473. (No model.)

To all whom it may concern:

Be it known that I, WALTER S. ADAMS, a citizen of the United States, and a resident of the city of Philadelphia, county of Philadelphia, and State of Pennsylvania, have invented a new and useful Improvement in Maximum-Traction Trucks, of which the following is a specification.

The object of my invention is to provide a truck of this class which will resiliently support the car-body at all times and which will be cheap, durable, and economical in operation. This object I accomplish by providing the truck with longitudinally and transversely disposed semi-elliptic springs which support the car-body and means independent of the springs for connecting the car-body and truck to receive all stresses incident to the propulsion of the car.

For a more particular description of one embodiment of my invention reference is to be had to the accompanying drawings, forming a part hereof, in which—

Figure 1 is a plan view of a truck provided with my improvement. Fig. 2 is an elevation of the same. Fig. 3 is a sectional view taken on the line 3 3 of Fig. 2 looking in the direction of the arrows.

Throughout the various views similar reference characters designate similar parts.

The truck contains the usual driving-wheels 1, connected by the axle 2, and the trailing wheels 3 and their connecting-axle 4. The axles 2 and 4 terminate in axle-boxes 5 and 6, which slide in pedestals 7 and 8 and support the same by the axle-box springs 9. The pedestals 7 and 8 are connected by chords 10, and arms 11 extend from the pedestals 7. Crossings 12 and 13 connect the arms 11 and chords 10, respectively. As this structure is old and well known in the art, a more detailed description is believed to be unnecessary.

A plate 14, with guides 15 and 16, is bolted to the crossing 12, and a similar plate 17, with guides 18 and 19, is secured to the crossing 13 or made integral therewith, as shown in Fig. 3. The functions of these guides will appear below.

Brackets 20 extend from the upper ends of

the pedestals 7 over the chord 10, and these 50 brackets are provided with upwardly-extending fingers 21 and 22, and between these fingers rest semi-elliptic springs 23, which extend over the chord 10 and arms 11 and are retained in their proper positions by the said 55 fingers and their bands 24. The upper portions of the bands 24 are raised sufficiently above the springs 23 to allow of the attachment of a swivel-plate 24^a, preferably of angle-iron form, adapted to make a pivotal connection with the car-body and also form an additional support therefor. The springs 23 are preferably placed with their concave sides uppermost, and at their ends shackles 25 are suspended, which engage and support upwardly- 60 arched and transversely-disposed semi-elliptic springs 26 and 27. The spring 26 is provided with a band 28, the upper surface of which forms a bearing 29, which engages a rub-plate 29^a, and is also provided with a projecting side 70 having an enlarged head 30, that engages the guides 18 and 19. This permits a free vertical movement of the band 28, but prohibits all other movement relative to the guides. A similar band 31 engages the spring 27 and has 75 a bearing 32, which contacts with a rub-plate 33, and projecting side with a head 34, which engages the guides 15 and 16 to limit the spring to a vertical movement.

The crossing 12 is provided with a horizontally-disposed guide 35, in which is a curved slot 36, which is concentric with the pivotal axis of the truck. This axis is placed close to the axle 2, as is customary in such structures. The walls of the slot 36 are 80 engaged by a pin 37, which is fixedly connected by brackets 38 to the sills 40 of the car-body. This structure permits the rigid framework of the truck to receive all stresses 85 incident to the propulsion of the car and relieves the spring from all stresses except those 90 incident to the resilient support of the car-body.

When the truck is in use and the weight of the car-body comes thereon, the bearing- 95 plates 29 and 32 are pressed downwardly, causing the springs 26 and 27 to flatten and splay the lower ends of the shackles 25 out-

wardly. The stresses are then transmitted through these shackles 25 to the springs 23, so that the load is equally distributed over four springs, which cause the car-body to be resiliently supported at all times. The shackles 25 are preferably made of two parts and linked together, so that the springs 23 will be relieved of all torsional stresses.

While I have shown and described one embodiment of my invention, it is obvious that many others may be made which employ its essential characteristics, and so I regard all structures as equivalents which come within the scope of the following claims.

Having thus described my invention, what I claim is—

1. In a truck or similar device, the combination of the wheels, axles, axle-boxes, pedestals, chords, and crossings with longitudinally-disposed semi-elliptic springs fixed to the pedestals and transversely-disposed semi-elliptic springs connecting said longitudinal springs.
2. In a truck or similar device, side frames, longitudinally-disposed semi-elliptic springs supported by said frames, and transversely-disposed semi-elliptic springs connecting said longitudinal springs and adapted to support a car-body.
3. In a truck or similar device, side frames, longitudinally-disposed semi-elliptic springs resting thereon, semi-elliptic springs supported by and connecting said longitudinal

springs, and means for causing said transverse springs to move in vertical planes. 35

4. In a truck or similar device, side frames, longitudinally-disposed semi-elliptic springs secured thereto, transversely-disposed semi-elliptic springs connected by said longitudinal springs and adapted to support a car-body, a crossing, and means adapted to connect a car-body with said crossing. 40

5. In a truck or similar device, side frames, longitudinally-disposed semi-elliptic springs supported by said side frames, means for connecting the ends of said springs, and bands for inclosing parts of said springs and coöperating with guides on the car-body. 45

6. In a truck or similar device, side frames with brackets protruding therefrom, semi-elliptic springs secured in said brackets, and means connecting the ends of said semi-elliptic springs. 50

7. In a truck or similar device, side frames with brackets protruding therefrom, a longitudinally-disposed semi-elliptic spring held by said brackets, a band on said spring, and a guide coöperating with said band. 55

Signed in the city and county of Philadelphia, State of Pennsylvania, this 27th day of August, 1903. 60

WALTER S. ADAMS.
